UNITED STATES PATENT OFFICE.

CHARLES D. ALLEN, OF NEW YORK, N. Y.

FLASH-LIGHT PHOTOGRAPHIC APPARATUS.

1,076,091.

Specification of Letters Patent.

Patented Oct. 21, 1913.

Application filed June 3, 1912. Serial No. 701,115.

To all whom it may concern:

Be it known that I, CHARLES D. ALLEN, a citizen of the United States, and residing at New York, in the county of New York and 5 State of New York, have invented certain new and useful Improvements in Flash-Light Photographic Apparatus, of which the following is a specification, such as will enable those skilled in the art to which it 10 appertains to make and use the same.

This invention relates to apparatus for use in connection with the production of flash light pictures, and the object thereof is to provide an improved portable apparatus of this class operated by the contraction and expansion of a compressible bulb so as to open the shutter of a camera simultaneously with the production of the light; and with this and other objects in view the 15 invention consists in an apparatus of the class specified constructed as hereinafter described and claimed.

The invention is fully disclosed in the following specification of which the accompanying drawing forms a part, said drawing being a diagrammatic view of my improved apparatus, and showing parts of the construction in section.

In the practice of my invention, I provide 30 what is known as a flash light bag *a* which may be suspended from any suitable support by means of cords or other devices *b*, or said bag may be otherwise supported, and is provided with an open folding bottom *c* which 35 is closed, in practice, by a cord *c*², or in any other way. Within the bag *a* is a transverse rod *d* from which is suspended a flash pan *d*² on which is placed an electric blasting fusee *d*³ over which the flash powder *d*⁴ is 40 placed and the fusee is provided with circuit wires *d*⁵ and *d*⁶ which extend through the bottom of the bag when said bottom is closed. I also provide a casing *e* which is 45 adapted to be held in one hand and one end of which is closed by a plug *e*² having binding posts *e*³ and *e*⁴, and said plug is provided with spring terminal arms *e*⁵ and *e*⁶ which are connected respectively with the posts *e*³ and *e*⁴, and said plug *e*² may be held in or 50 secured in the casing *e* by a binding screw, or in any other way. The inner ends of the terminal arms *e*⁵ and *e*⁶ are provided with contact heads *e*⁷ and *e*⁸, and the head *e*⁸ of the contact arm *e*⁶ rests on an expansible bag *f*, while the position of the head of the arm *e*⁵ may be adjusted by means of a set 55

screw *f*². Connected with the bag *f* and communicating therewith is a tube *g* which may be held in the casing *e* or secured therein in any desired manner, and which is provided with a nozzle *g*² which projects through the closed end of said casing and with which is connected an ordinary air bulb *h* with which is connected a flexible tube *h*² which is also connected with the shutter *i* of the camera, in the usual manner. The shutter *i* may be of any preferred construction, but is preferably what is known as a bull's eye shutter, and the shutter blades *i*² thereof are opened and closed by 60 the compression of the bulb *h*. I also provide a battery *j* which is of small voltage, and which may be carried in the pocket, if desired, and this battery is provided with a wire *j*² which is connected with the binding post *e*⁴ of the casing *e*, and with another circuit wire *j*³ which is connected with the circuit wire *d*⁶ of the fusee *d*³, and another circuit wire *k* connects the binding post *e*³ with the circuit wire *d*⁵ of said fusee *d*³. 65 The casing *e* is small and may be carried in a pocket, and the entire apparatus with the exception of the bag *a* and the camera may also be carried in a pocket.

The operation will be readily understood, 70 from the foregoing description when taken in connection with the accompanying drawing and the following statement thereof. The bag *a* may be suspended at any point, in a room, office, compartment or hall, 75 where it is desired to take a flash light picture, and the circuit wires having been connected, and the tube *h*² having been connected with the camera the casing *e* and bulb *h* are grasped in the hand and pressure is applied to said bulb. This pressure expands the bag *f*, and this expansion of the bag *f* closes the circuit, the terminals of which are formed by the arms *e*⁵ and *e*⁶, and a circuit is completed through the fuse *d*, and the 80 flash light is produced, and instantaneously with this production of the light and at the moment when said light is most intense the shutter of the camera is opened and an exposure made.

I am aware that apparatus somewhat similar to this have heretofore been made, but in all of said apparatus, the opening of the shutter has not been and cannot be timed so as to correspond with the production of the maximum light, but with my improvement this timing of the opening of 85 90 95 100 105 110

the shutter with the point of time at which the maximum of light is produced is made exact. The screw f^2 controls the distance between the two terminal spring arms e^5 and e^6 and thereby controls the distance through which the arm e^6 must move, and thus controls the time required for the closing of the circuit, and by means of this construction the circuit closing device may be operated for the taking of pictures in one-fifth of a second or faster, as one-fiftieth or 10 one-two hundred and fiftieth of a second.

It will be understood that with my improved apparatus the smoke produced by 15 the flash light is contained in the bag a , and this smoke may be discharged from said bag through a window or otherwise after the operation of producing the light, and this, as will be understood, prevents the 20 filling of the room, compartment or hall, in which the picture is taken with the smoke and disagreeable odors produced by the explosion.

The bag a may be compactly rolled up or 25 folded up into convenient form for packing, carrying or shipping purposes, but the details of the construction of this bag are not claimed herein, as they will form the subject of a separate application, which I intend to file, and it will be understood, that 30 the casing e described and claimed herein, may be used with any kind or class of a

flash light producing apparatus using explosive powders, and independent of the flash bag a , if desired.

Having fully described my invention what I claim as new and desire to secure by Letters Patent is:—

In a flash light apparatus, a circuit closing and breaking device adapted to be held 40 in the hand, and comprising an oblong casing one end of which is closed by a plug provided with binding posts and with spring arm terminals which extend into said casing and which are connected with 45 said posts, an expansible bag placed between the free end of one of said terminals and the adjacent wall of the casing and adapted to force said terminal into contact with the free end of the other terminal, a screw 50 passing through one side of the casing and bearing on the free end of said other terminal and adapted to adjust the position thereof, and a tube communicating with said bag and extending through the end of said 55 casing opposite that closed by said plug.

In testimony that I claim the foregoing as my invention I have signed my name in presence of the subscribing witnesses this 28th day of May 1912.

CHARLES D. ALLEN.
